FLOODLIGHT

Jose A. Hernandez, Houston, Tex., assignor to Esquire, Inc., New York, N.Y.

Filed Mar. 30, 1970, Ser. No. 22,091

Term of patent 14 years

Int. Cl. D26—02

U.S. Cl. D48—20

FIG. 1

FIG. 2

FIG. 3

FIG. 4

FIG. 5

FIG. 1 is a perspective view of a floodlight embodying my design, as seen from the bottom, front, and one side thereof;

FIG. 2 is another perspective view thereof as seen from the top, rear and opposite side;

FIG. 3 is a side elevational view thereof on a reduced scale;

FIG. 4 is a bottom plan view thereof on a reduced scale; and

FIG. 5 is a front elevational view thereof on a reduced scale.

I claim:

The ornamental design for a floodlight, substantially as shown and described.
